UNITED STATES PATENT OFFICE

WILLIAM B. TINSLEY, OF PAMPA, TEXAS

FLEXIBLE JOINT PACKING BOX

Application filed March 30, 1931. Serial No. 526,382.

My present invention has reference to a joint packing box for use in connection with oil or water pumping apparatus and my object is the provision of a packing box which is flexible so that the same will give or flex to retain itself in a line with the polish rod in the slight backward and forward movement of the rod and thus prevent wear on either the packing box or the rod and also insure a fluid tight joint.

The invention will be fully and comprehensively understood from a consideration of the following detailed description when read in connection with the accompanying drawings which form part of the application, with the understanding, however, that the improvement is capable of extended application and is not confined to the exact showing of the drawings nor to the precise construction described and, therefore, such changes and modifications may be made therefrom as do not affect the spirit of the invention nor exceed the scope thereof as expressed in the appended claim.

25 In the drawings:

Figure 1 is a side elevation of the improvement in applied position.

Figure 2 is a side elevation of the improvement.

30 Figure 3 is a central longitudinal sectional view therethrough.

Figure 4 is a sectional view through the upper portion of the bottom of the fixed joint section.

35 Figure 5 is a sectional view approximately on the line 5-5 of Figure 3.

Figure 6 is a bottom plan view of a cap.

In Figure 1 of the drawings I have illustrated a pumping apparatus provided with the improvement. In this figure the numeral 10 designates the derrick, 11 the derrick floor, 12 the Samson post for the beam 13 on whose inner end there is connected the polish rod 14. The beam 13 has its center supported on the Samson post and the beam is imparted an upward and downward swinging movement by the turning of an engine which operates a crank that is connected with the beam. As these parts are of the usual construction they have not been illustrated by the drawings.

By reference to the full and dotted line positions of the beam and polish rod it will be seen that the upward and downward swinging of the beam causes a slight but determined forward and backward pull on the polish rod, 55 and the result is that when a joint of the ordinary construction is connected between the polish rod and the joint therefor a continuous wear will be occasioned between the packing joint and the rod which results in 60 the wearing of both of these members and consequently an unreliable and leaky joint. It is the purpose of this invention to overcome such leaky joints by providing a flexible joint packing box for the polish rod. 65

The joint, in Figure 1, is broadly indicated by the numeral 15, the polish rod working through this joint and having connected thereto the usual string of rods that extend to the bottom of the well and working the 70 pump when the polish rod is vertically reciprocated.

The T which connects the fixed member of the flexible joint 15 with the well tubing is indicated by the numeral 16 and the flow 75 pipe, which directs the oil or water to the tanks and which is screwed in the central branch of the coupling 16, is indicated by the numeral 17, while the casing head to which the T is also connected is indicated by the 80 numeral 18 and the casing by the numeral 19.

The lower and fixed member of my improved flexible joint packing box includes a lower tubular part 20 which is screwed in the upper end of the T-coupling 16. The top of 85 the lower member merges into a hollow substantially semi-spherical head 21 and in this head there is received the hollow spherical head 23 of the upper tubular member 24 of the joint. The head 23 is greater than one-half of a circle, and is mounted for turning in the head 21, there being a ground joint between the heads. The head 23, at the junction of the tubular portion and the stem is formed with a shoulder 25 that is contacted 90 by an angle lip 26 provided by flanging inwardly the central open portion of a hollow substantially semi-spherical cap 27. The cap 27 has its widened edge formed with an outstanding continuous flange 28 and the said 100

flange has its periphery preferably widened outwardly at rightangularly disposed points so that the flange is not weakened by bolt openings 29 that pass therethrough. The 5 mouth of the cup-shaped head 21 is also formed with an outwardly directed flange 30 that may be provided with peripheral enlargements disposed opposite the peripheral enlargements of the flange 28 and through 10 which the bolts pass and against which flange 30 the heads of the bolts rest. The bolts pass freely through the openings in the flange 28 of the cap and are received through washers 31. The bolts are engaged by nuts 32 that 15 contact with the washers 31 and surrounding the bolts and exerting a pressure between the washers 31 and the flange 28 of the cap there are helical pressure springs 33. These 20 springs force the saucer-shaped head 21 of the lower joint member into tight frictional engagement with the substantially semi-spherical head 23 of the upper joint member and likewise force the cap tightly against the head of the upper joint member. 25 The polish rod 14, of course, passes through the joint members and the tubular portion 24 of the upper joint member has fixed in the lower portion of the bore thereof a bushing 34 that affords a stop for a 30 packing 35 which is arranged in the bore of the tubular portion 24 and which packing is forced against the polish rod by a bushing which is in the nature of a follower member 36. The packing is adjustably compressed against the polish rod through the 35 medium of a cap nut 37 which is screwed on

the outer end of the tubular portion 24 and the flexible joint box and whose inner shoulder contacts with the head of the packing follower member 36.

My improved flexible joint packing box 70 for polish rods will have its upper portion, which carries the packing, yield with and in timed relation to any yielding or forward and rearward, or as a matter-of-fact, in any direction of the polish rod 14 so that air between the polish rod and the packing box is effectively prevented. The flexible packing box insures a fluid tight joint between the polish rod and the T joint 16 and it is believed the construction and advantages will 75 be understood and appreciated by those skilled in the art to which the invention relates without further detailed description.

Having described the invention, I claim:

A flexible joint of the character described 80 comprising a pair of semi-spherical inter-fitted members having centered tubular pipe extensions, an external shoulder formed on one of the members, a semi-circular cap telescoped over the shouldered member and having a circular angular lip concentrically disposed with respect to the pipe extension of said member and resting against the shoulder, bolt members joining the cap with the other member, and expansion springs acting 85 with the bolts to compress the interfitted members and tensioning the cap relative thereto.

In testimony whereof I affix my signature.

WILLIAM B. TINSLEY.
